UNITED STATES PATENT OFFICE.

ROSWELL L. FAIRBANK, OF DEANSVILLE, NEW YORK.

REVERSIBLE BACKS FOR LOUNGES.

SPECIFICATION forming part of Letters Patent No. 224,082, dated February 3, 1880.

Application filed October 7, 1879.

To all whom it may concern:

Be it known that I, ROSWELL L. FAIRBANK, of Deansville, in the county of Oneida and State of New York, have invented a new and valuable Improvement in Reversible Backs for Lounges; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of my invention. Fig. 15 2 is a transverse section with back removed. Fig. 3 is a detail view of one of the locking-plates and escutcheons; Fig. 4, a detail view of a modification of the adjustable rods with coupling-nut.

20 The present invention has relation to lounges or couches; and it consists in the peculiar manner of connecting the backs thereof, whereby they are detachable and reversible from one side of the lounge to the other, as will be hereinafter described.

In the accompanying drawings, A represents the frame of the lounge, of any suitable form and design, having the usual seat and head-rest; and B represents the back of the 30 lounge, which may also be of any suitable form and design, and, if desired, each end thereof may be a duplicate of the other. This back is made detachable and connected to the frame A in such a manner as will admit of its being readily changed from one side of the lounge-frame to the other. To accomplish this result there pass through the sides of the frame A two or more rods, a, provided with screw-threads upon their ends to 40 receive headed screw sleeves or nuts b. Although I have shown this means of connection, it is evident that the construction of the rods may be variously modified without departing from my invention, such as having two 45 sections of rods headed upon their outer ends and connecting with a take-up or screw-coupling nut at their inner ends, as illustrated in Fig. 4, as the purpose is to have a rod with heads upon its outer ends and adapted to slide longitudinally to bring the heads a sufficient distance out from either side of the

lounge-frame to connect the back B. This back is provided with holes c, around which are secured escutcheons d, and to the back B or to the escutcheons d are secured, by screws 55 or other suitable means, locking-plates e, for securing the back B in place and preventing the same from becoming detached from the rods and nuts a b.

The back B may be, if found desirable, upholstered on both sides, thereby simply changing it from one side to the other without the necessity of changing or reversing the ends.

When the reversing of the back is found necessary, the rods, with their headed ends, after 65 the back has been detached, are pushed through so as to have the opposite ends of the rods project beyond the opposite side of the lounge-frame a sufficient distance to admit of the openings c being passed over the 70 heads of the rods. The locking-plates e are then brought into position, and firmly lock or secure the back against the frame of the lounge, thereby enabling any one to adapt the lounge to be placed in any convenient position 75 in any room. The rods a, being screw-threaded upon their ends with a sleeve or take-up, admit of their being adjusted in length to any variation that may occur in upholstering the 80 frame.

Having now fully described my invention, what I claim as new, and desire to secure by Letters Patent, is—

1. The lounge-frame A, having the horizontal transversely-adjustable rods, in combination with the detachable and reversible back B and means, substantially as described, for connecting said back to either end of the rods, as set forth.

2. The horizontal rods a, transversely-adjustable with relation to the lounge-frame A, in combination with the reversible back B, provided with opening c and locking-plates e, substantially as and for the purpose specified.

In testimony that I claim the above I have 95 hereunto subscribed my name in the presence of two witnesses.

ROSWELL L. FAIRBANK.
